HOLDER FOR GLASSES OR TICKETS

Lyon D. Evans, 13 Stoneman Ave.,
Lakewood, N.Y. 14750

Filed Feb. 20, 1968, Ser. No. 10,649

Term of patent 14 years

Int. Cl. D6—01

U.S. Cl. D57—1

FIG. 1 is an isometric view of the holder for glasses or tickets embodying my new design, with the ticket shown in broken lines for illustrative purposes only. (MPEP 1503.02, par. 2).

FIG. 2 is an end view thereof.

FIG. 3 is a plan view thereof.

I claim:

The ornamental design for a holder for glasses or tickets, as shown and described.
